UNITED STATES PATENT OFFICE.

HERMANN VON MITZLAFF, OF POTSDAM, PRUSSIA, GERMANY.

HYDRAULIC BRICK-MACHINE.

SPECIFICATION forming part of Letters Patent No. 394,528, dated December 11, 1888.

Application filed January 12, 1888. Serial No. 260,489. (No model.)

To all whom it may concern:

Be it known that I, HERMANN VON MITZLAFF, a subject of the King of Prussia, residing at Potsdam, in the Kingdom of Prussia and Empire of Germany, have invented new and useful Improvements in Brick-Machines, of which the following is a specification.

My invention consists in an improved brick-machine, the novel features of which are fully pointed out in the following specification and claims, and illustrated in the accompanying drawings, in which—

Figure 1 represents a sectional side elevation. Fig. 2 is an end elevation. Fig. 3 is a plan or top view. Fig. 4 is a vertical central section of a lower press-cylinder and its plunger, drawn to a larger scale than the preceding figures. Fig. 5 is a similar section of an ejector. Fig. 6 is a vertical central section of an upper press-cylinder. Fig. 7 is a vertical section in the plane $x x$, Fig. 8, of a mold. Fig. 8 is a horizontal section of the same in the plane $y y$, Fig. 7. Fig. 9 is a vertical section in the plane $z z$, Fig. 10, of a detail part. Fig. 11 is a vertical central section of a supply-valve with the plunger adjusted to supply water to the cylinders. Fig. 12 is a similar view thereof, showing the plunger adjusted to shut off the supply and open the discharge. Fig. 13 is a central section of a supply-regulating valve. Fig. 14 is an end view of the valve-disk thereof.

Similar letters indicate corresponding parts. In the drawings, the letter A designates the stationary bed of the press-frame, in which are secured two press-cylinders, B B', and two ejector-cylinders, C C'.

Above the bed A, and loosely mounted upon a vertical shaft, D, is located a horizontal rotary mold-carrier, E, which in this example is provided with six molds, F, arranged equally distant from the center. Above said mold-carrier is arranged a stationary bridge, G, which is supported at each end on pillars G' G', resting on and secured to the bed A. The upper press-cylinders, B² B³, are secured in said bridge above and in line with the lower cylinders, B B'. An intermittent rotary motion is imparted to the mold-carrier E, so as to bring the molds F successively between the

cylinders B and B² and B' and B³ by the following means: A driving-shaft, H, at the top of the frame is provided on one end with a gear-wheel, h, which meshes into a gear-wheel, h', on a counter-shaft, I, extending parallel to shaft H. A toothed segment, h², on the face of said gear-wheel h' engages with a bevel-wheel, h³, mounted on the upper end of a vertical spindle, H', whereby an intermittent rotary motion is imparted to the latter. A gear-wheel, h⁴, on said spindle H' meshes into gear-teeth h⁵ on the periphery of the mold-carrier E. The toothed segment h² is of such length that for one revolution of the driving-shaft H the mold-carrier is moved, in this example, through one-sixth of a revolution, so that a new set of molds is brought between the pressure-cylinders at each revolution of the shaft.

The lower press-cylinders, B B', Fig. 4, are each constructed with two distinct and separate chambers, a a', the upper or main chamber, a, being considerably larger in diameter than the lower or supplementary chamber, a'. In these chambers are fitted plungers b and b', which are rigidly connected with each other to form a compound plunger, said plungers having different diameters. Liquid under pressure is admitted simultaneously to both chambers a a', and the plunger b b' is rapidly forced outward under the force acting on the plunger b' alone, as the chamber a is so large in comparison with the chamber a' that the water merely fills the former as the piston advances. As the resistance of the mass in the molds to compression increases, the pressure of water also acts on the plunger b, and a great force is exerted on the mass near the completion of the stroke, owing to the large area of the plunger b. The water under pressure enters the chamber a' at a² and the chamber a at a³.

The length of the stroke of the compound plunger b b' is adjusted by means of a screw-cap, b*, engaging with the cylinder when the plunger is at the end of its stroke. A second inlet, a⁴, in the chamber a' is provided, for the purpose of admitting the water to force the plunger inward at its non-working stroke, as will be hereinafter more fully described. In this case the force of the water comes on a shoulder formed by the cap b*, said

fitting closely to a contracted portion of the chamber a' . The upper press-cylinders, Fig. 6, are constructed similarly to the lower press-cylinders just described and operate in the same manner.

The molds F, Figs. 1, 3, 7, and 8, are divided into two or more compartments of the dimensions desired by double partitions j' , and are removably secured to the mold-carrier by the use of keys. Said molds consist of an internal steel box, J, open at its top and bottom, and an external box, J', of cast-iron, air-spaces being left between the two. The compartments of the mold are adapted to be entered from the top and bottom by suitable punches, L L, secured to the plungers b' of the upper press-cylinder, and from below they are entered by similar punches, L' L', secured to cross-heads L², vertically movable on guide-rods l, pendent from the bodies of the molds F. The ends of the rods l are threaded and provided with nuts j. By turning said nuts the punches can be made to project more or less into the molds, so that they will receive more or less of the material to be compressed. Said cross-heads are adapted to be engaged by the plungers b b' of the lower cylinders, B B', when the mold-carrier is rotated in the proper position.

To provide for the escape of air from the material under compression, the walls of the inner box, J', as well as the partitions, are provided with perforations or air-holes k, and head-plates j² on the punches, Fig. 6, may be similarly perforated, so that the air may escape at all sides. In order to prevent the holes k from becoming clogged, the partition is made as thin as practicable at the portion containing the holes by rabbeting or cutting away the material of the box J and the partitions, and the holes are drilled tapering, with the greater diameter outward. To prevent the mold-carrier from yielding vertically, and also to provide a comparatively frictionless bearing for the same, I construct a bearing, Figs. 9 and 10, of two steel rings, m, which are secured to the shaft D, and between which rings a number of conical rolls, m' m', can play, all said rolls pointing to a common center. The rolls rotate about spindles secured in a collar, m², loosely encompassing the stationary shaft D. Two such devices are placed at a distance apart on the shaft, Fig. 1.

The ejectors C C' are secured to the bed A diametrically opposite to each other, and each of the same, Fig. 5, is provided with two chambers, c c', the main chamber c having a slightly smaller bore than the supplementary chamber c', and the plunger C², fitted in said chambers, is made smaller in diameter in its upper portion, thereby forming an annular water-space with the walls of the upper chambers. The water under pressure is admitted at c² near the bottom of the chamber c, and at c³ at the top of the chamber c'. The water entering the inlet c² forces the plunger upward, and the downward or return stroke is quick-

ened by the water-pressure on the shoulder c*, formed at the junction of the two portions of the plunger.

The arrangement of pipes for distributing water to the various cylinders from an accumulator or hydraulic press (not shown) and the various valves in said pipes and means for operating the same are as follows:

M M', Figs. 1, 2, and 3, are the supply-pipes from the accumulator or hydraulic press, which are connected to the inlets of two supply-valves, N N', Figs. 1, 2, and 3, the construction of which latter is shown in Figs. 11 and 12. Each of said valves consists of a casing provided with an inlet, n, connected to the accumulator, two outlets, n' n², opening to the distributing-pipes of the various cylinders, and a discharge, n³, for the water discharged from the said cylinders. A plunger having a neck and two heads, n⁴ n⁵, controls said openings. When the plunger n⁴ n⁵ is in the position shown in Fig. 11, the water from the supply-pipe M' can enter the valve-casing, and passes out through the two outlet-openings n' and n² to the various cylinders, since the discharge n³ is closed by the head n⁵. When the plunger is moved to the position shown in Fig. 12, the two outlet-openings n' and n² are closed by the head n⁵, and the discharge from the various cylinders enters the casing through the outlet-openings n' and n² and discharges through the opening n³.

The plunger n⁴ n⁵ of each valve is reciprocated once for each revolution of the shaft I by a suitable connection with the latter. In the drawings, Figs. 1, 2, and 3, I have shown as a driving mechanism for each plunger a hub, I', having an eccentric groove, i, which hub is rigidly mounted on said shaft. One arm of a crank-lever, i', engages the groove i, and the second arm of the lever is connected by a rod, i², with an arm, i³, extending from a rock-shaft, i⁴. A second arm, i⁵, projecting from the said rock-shaft, is in engagement with the plunger N². To the outlet-openings n' n² of the valve N are connected two pipes, P and Q, one of which, P, extends along the side of the press, and its end is connected with the supplementary chamber a' of the lower press-cylinder B, to supply water to the same. A branch pipe, P', extending upwardly and horizontally, is connected by auxiliary branches p p' with the supplementary chambers of the two upper press-cylinders, B² and B³. The second pipe, Q, from the valve N connects directly with the supplementary chamber a' of the cylinder B'.

A branch pipe, p², from the pipe P is connected with the main chamber c of the ejector C. To the outlet-openings n' n² of the valve N' are connected two pipes, R and S, one, R, of which extends along the side of the press, and its end connects with the main chamber a of the lower press-cylinder, B'. A branch, R', of said pipe extends upwardly and horizontally, and is connected by two branch pipes, r r', with the main chambers of the two

upper press-cylinders, B^2 and B^3 . The second pipe S from the valve N' connects directly with the main chamber of the lower press-cylinder, B' . A branch pipe, r^2 , is connected with 5 the supplementary chamber of the ejector C .

From this description it will be seen that the supply-valve N is connected with the supplementary chambers a of the four press-cylinders B , B' , B^2 , and B^3 , and the valve N' 10 with the main chamber a' of the same cylinders.

In the operation of the press the valves N N' are opened for the admission of water, and the plungers b b' of the said cylinders are 15 started on their working stroke under a comparatively small pressure, owing to the small diameters of the plungers b' in the supplementary chambers. When the plungers have 20 been moved through a part of their stroke and the resistance of the material increases, the water in the main chambers a acts on the large plungers b , causing the punches to act with great force upon the mass within the 25 molds K during the remaining part of the stroke, whereby the brick is rendered extremely compact and sound.

The regulation of the velocity with which the plungers move being an important matter, I provide valves T T' , Fig. 13, for this purpose, which can be inserted in the pipes Q R S . Each of said valves consists of a casing 30 having an inlet, t , and an outlet, t' . A valve-disk, T^2 , within the casing is guided vertically to and from its seat, and is provided with a 35 number of orifices, t^2 . The entering liquid presses the valve down to its seat, but can pass through said orifices. To regulate the quantity of liquid passing through the valve, any desired number of said orifices t^2 can be 40 plugged with suitable screws, the orifice being provided with internal screw-threads.

The discharging water enters the outlet t' and lifts the valve-disk T^2 from its seat, so that it passes unobstructedly through the 45 valve. Any other suitable valve can, however, be used to accomplish this object.

To draw the plungers of the press-cylinders B B' B^2 B^3 inward on their non-working stroke after the completion of the working stroke, I 50 connect the inlets a^4 of the supplemental chambers, by means of pipes v^3 , with the supply-pipe from the accumulator, so that after the valve N^2 closes the supply the pressure of 55 the water will act on the ends of the caps previously described, on the plungers b b' , and on the shoulders c^* of the plungers C^2 , to force the plungers on their non-working stroke. The inlets c^3 of the ejectors C C' are similarly 60 connected to the said supply-pipes.

With material which requires an extremely high and long-continued pressure I make use of a carrier containing eight molds instead of six. In this case the material in the mold before being subjected to the action of the 65 presses under full water-pressure is subjected to the action of presses under a lighter pressure, and then the molds are carried

around to the main presses. The material is thus subjected to a threefold pressure—first, by the auxiliary presses, then by the first 70 light pressure of the main presses, and, finally, to the full pressure of said main presses. In this case two molds are at one time under the main presses, two under the ejector, and two are being filled.

What I claim as new, and desire to secure by Letters Patent, is—

1. The combination, in a hydraulic brick-press, of the fixed base A , the hydraulic press-cylinders B B' , fitted to the base and containing 80 plungers operated by fluid-pressure, pipes for supplying the fluid, an intermittently-rotating mold-carrier, E , and ejectors C C' , substantially as described.

2. The combination, in a hydraulic brick-press, of the fixed base A , the hydraulic press-cylinders B B' , fitted to the base and containing 85 plungers operated by fluid-pressure, an intermittently-rotating mold-carrier, E , hydraulic ejector-cylinders C C' , containing 90 plungers operated by fluid-pressure, and a system of pipes for supplying the fluid to the press and ejector cylinders, substantially as described.

3. The combination, in a hydraulic brick-press, of a stationary base, A , pillars G' , rising from the base, a stationary bridge, G , mounted on the cylinders, upper and lower hydraulic press-cylinders fitted, respectively, to the base and the bridge, and containing plungers operated by fluid-pressure, an intermittently-rotating mold-carrier between the respective 100 press-cylinders, and a system of pipes supplying the fluid to the press and ejector cylinders, substantially as described.

4. The combination, in a hydraulic brick-press, of the fixed base A , the hydraulic press-cylinders B B' , and the ejector-cylinders C C' , fitted to the base and each cylinder containing a plunger operated by fluid-pressure, with 110 the intermittently-rotating mold-carrier E , the guide-rods l , depending from the said carrier, and the cross-heads L^2 , sliding vertically on the guide-rods and provided with punches L' , substantially as described.

5. The combination, in a hydraulic brick-press, of the stationary base A , the pillars G' , rising therefrom, the bridge G on the pillars, the vertical shaft D , seated at its ends in the base and bridge, upper and lower hydraulic 120 press-cylinders fitted, respectively, to the bridge-base, and each containing a reciprocating plunger, the ejector-cylinders C C' , a system of pipes for supplying the fluid to the cylinders, the intermittently-rotating mold-carrier mounted on the vertical shaft and provided with an annular gear, a gear-wheel engaging the latter, a rotary drive-shaft, and a segmental gear driven by the drive-shaft and intermittently rotating the gear-wheel which 125 engages the annular gear on the mold-carrier, substantially as described.

6. The combination, in a hydraulic brick-press, of the base A , the pillars G' , the sta-

- tionary bridge G on the pillars, the vertical shaft D, upper and lower hydraulic press-cylinders fitted, respectively, to the bridge and base, and each containing a plunger operated by fluid-pressure, the punches L on the plungers of the upper cylinders, the intermittently-rotating mold-carrier E, mounted on the vertical shaft, the guide-rods l , depending from the mold-carrier, the cross-heads L^2 , movable vertically on the guide-rods and provided with punches L' , ejector-cylinders C C', fitted to the base, and a system of pipes for supplying fluid to all the cylinders, substantially as described.
- 15 7. The combination, in a brick-press, of the base A, presses B B', and ejectors C C', fitted to the base, a vertical shaft, D, an intermittently-rotating mold-carrier, E, centrally mounted on the shaft and having an annular gear at its periphery, a gear-wheel, h, engaging the annular gear, a gear-wheel, h^2 , having a segmental gear, h^3 , for intermittently rotating the gear-wheel engaging the annular gear on the mold-carrier, and a driving-shaft 20 for operating the gear-wheel carrying the segmental gear, substantially as described.
- 25

8. The combination, in a brick-press, of the base A, presses B B', and ejectors C C', fitted to the base, a vertical shaft, D, an intermittently-rotating mold-carrier, E, mounted on the shaft, guide-rods l , depending from the mold-carrier, and cross-heads L^2 , sliding vertically on the guide-rods and provided with the punches L' , substantially as described.

9. The combination, with the presses, the vertical shaft, and the mold-carrier centrally journaled on the shaft, of the upper and lower rings, $m m$, secured to the shaft, the inner annular collar m^3 , loose on the shaft, and the conical rollers m' , each having a horizontal shaft supported at its inner end by the collar, substantially as described.

In testimony whereof I have hereunto set my hand and seal in the presence of two subscribing witnesses.
